CLAIM

The ornamental design for a tow harness for inflatable tube,
as shown and described.

DESCRIPTION

FIG. 1 is a top and left side perspective view of a tow harness for inflatable tube showing my new design, the broken lines are for illustrative purposes only and form no part of the claimed design;

FIG. 2 is a side elevational view of the tow harness shown in FIG. 1;

FIG. 3 is a front elevational view of the tow harness;

FIG. 4 is a rear elevational view of the tow harness;

FIG. 5 is a top plan view of the tow harness;

FIG. 6 is a bottom plan view of the tow harness; and,

FIG. 7 is a fragmentary portion of the right end side of the harness on a greatly enlarged scale.
